CLAIM

The ornamental design for a pocketed leaf for video index tabs or similar article, as shown and described.

DESCRIPTION

FIG. 1 is a front perspective view of a pocketed leaf for video index tabs or similar article showing my new design;

FIG. 2 is a right side elevational view thereof;

FIG. 3 is a top plan view thereof, the undisclosed bottom being a mirror image;

FIG. 4 is a front elevational view thereof, the undisclosed rear being flat and plain;

FIG. 5 is a front perspective view of a tab thereof, shown separately for clarity of illustration only;

FIG. 6 is a bottom plan view thereof, the undisclosed top being a mirror image;

FIG. 7 is a right side elevational view thereof;

FIG. 8 is a front elevational view thereof, the undisclosed rear being flat and plain; and

FIG. 9 is an enlarged fragmentary view of a corner of the leaf with a tab in a partially inserted position.

FIG. 1

FIG. 3
